(57) **CLAIM**

The ornamental design for a ball marking tool, as shown and described.

DESCRIPTION

FIG. 1 is a front perspective view thereof;

FIG. 2 is a top plan view thereof;

FIG. 3 is a left side view thereof;

FIG. 4 is a front elevational view thereof;

FIG. 5 is a bottom plan view thereof; and,

FIG. 6 is a rear elevational view thereof.

The golf ball depicted by means of broken lines has been shown for illustrative purposes only and forms no part of the claimed design.
